UNITED STATES PATENT OFFICE.

ALBERT A. RANKIN, OF SCHENECTADY, NEW YORK.

OVEN.

1,162,399.

Specification of Letters Patent.

Patented Nov. 30, 1915.

Application filed May 17, 1915. Serial No. 28,550.

To all whom it may concern:

Be it known that I, ALBERT A. RANKIN, a citizen of the United States, residing at Schenectady, county of Schenectady, and State of New York, have invented certain new and useful Improvements in Ovens, of which the following is a specification.

Reference may be had to the accompanying drawings, and the reference characters marked thereon, which form a part of this specification. Similar characters refer to similar parts in the several figures therein.

This invention relates to ovens for baking or drying various articles.

Certain objects of the invention are to facilitate the loading of the articles into the oven and their removal therefrom; and to permit practically continuous operation of the oven.

Other objects will appear in connection with the following description.

Figure 1 of the drawings is a horizontal cross-section of an oven embodying my invention. Fig. 2 is a vertical cross-section of the same taken on the broken line 2—2 in Fig. 1.

Referring to the drawings wherein the invention is shown in preferred form, 1 is a heated inclosure which may be of any desired shape provided with a side-opening, 2, in one of its vertical walls. A hollow upright cylinder or drum, 3, is rotatively mounted within the inclosure in position to occupy said side-opening, 2. The cylinder 35 may be so rotatively mounted in any known manner. I have shown the cylinder, 3, mounted upon a turn-table, 4, supported upon ball-bearings, 5.

The cylinder, 3, has a central, vertical partition, 6, dividing its interior into two compartments, 7 and 8, and the cylinder is provided with side-openings, 9, communicating with said respective compartments.

Each of the side-openings, 9, in the cylinder is adapted to register with the side-opening, 2, in the inclosure, and the portions of the cylinder-walls between said opening, 1, in the inclosure, and the portion of the side-opening, 2, in the inclosure at certain times.

Brackets, 10, extend across the respective compartments, 7 and 8, at right angles to the central partition, 6, and serve to removably support shelves, 11, upon which the articles to be treated are placed.

The spaces between the side-edges of the shelves and the closed portions of the cylinder-wall between the side-openings, 9, are provided with horizontal open-work partitions, 12, preferably formed by wire-screens, which partitions are substantially in the plane of the shelves, 11, and serve as supports for articles to be treated, while permitting circulation of the heated air around and between the shelves.

The cylinder, 3, may be rotated by hand, or in any known manner, as by a cable, 13, passing around the cylinder and connected with suitable operating-mechanism, not shown.

The interior of the inclosure, 1, may be heated in any known manner to such temperature as is desired for the treatment of the particular articles.

I have shown a series of steam-pipes, 14, along the side-walls of the inclosure, 1, which provide a sufficient degree of heat for many purposes.

The operation of the oven is as follows: The cylinder, 3, is rotated to cause one of its side-openings, 9, to register with the side-opening, 2, in the inclosure, thus affording ready access from outside the inclosure, 1, for loading and unloading the articles upon the shelves, 11, and screens, 12. A load having been placed in one of the compartments, the cylinder is rotated 180 degrees causing the other side-opening, 9, to register with the side-opening, 2, in the inclosure, and bringing the first-heated compartment into communication with the heated interior of the inclosure. The drying of the articles in the first-loaded compartment thus proceeds while the other compartment is being loaded. When both compartments are loaded, the cylinder is rotated to bring one of its closed side-portions across the side-opening, 2, of the inclosure, thus closing said opening, while leaving both compartments, 7 and 8, open to the interior of the inclosure.

What I claim as new and desire to secure by Letters Patent is—

1. In an oven, and in combination, a heated inclosure provided with a side-opening; and an upright hollow cylinder rotatively mounted within the inclosure in position to occupy said side-opening, and provided with a side-opening adapted to communicate with the interior of the inclosure in one rotative

position of the cylinder, and to register with the side-opening in the inclosure in another rotative position of the cylinder.

2. In an oven, and in combination, a heated inclosure provided with a side-opening; an upright hollow cylinder rotatively mounted within said inclosure in position to occupy said side-opening, and having a portion of its body adapted to close said side-opening in one rotative position of the cylinder and being provided with a side-opening adapted to register with the side-opening in the inclosure in another rotative position of the cylinder.
- 10 3. In an oven, and in combination, a heated inclosure provided with a side-opening; and an upright hollow cylinder rotatively

mounted within the inclosure in position to occupy said side-opening, and having a vertical partition whereby it is divided into compartments, said cylinder being provided with side-openings into the respective compartments adapted to severally register with the side-opening in the inclosure and having intermediately of its said side-openings closed portions adapted to severally close said side-opening in the inclosure.

In testimony whereof, I have hereunto set my hand this 4th day of May, 1915.

ALBERT A. RANKIN.

Witnesses:

GEO. W. FEATHERSTONHAUGH,
HARRIETT N. BORDEN.
